CLAIM

We claim the ornamental design for a fishing rod holder, as shown and described.

DESCRIPTION

FIG. 1 is a front perspective view of our new design; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The views of the fishing rod holder not shown form no part of the design of this claim. The dash-dash lines in the figures show optional features that form no part of the design of this claim. The wavy dash-dash lines and brackets combine to reflect that the wavy dash-dash lines and the area in between the bracketed pairs of dash-dash lines forms no part of the design of this claim.
